(57) **CLAIM**

The ornamental design for the audio speaker component, as shown.

DESCRIPTION

FIG. 1 is a top view of the audio speaker component of this invention.

FIG. 2 is a side view of the audio speaker component taken along lines 2—2 of FIG. 1.

FIG. 3 is a bottom view of the audio speaker component.

FIG. 4 is a side view of the audio speaker component taken along lines 4—4 of FIG. 1.

FIG. 5 is a side view of the audio speaker component taken along lines 5—5 of FIG. 1.

FIG. 6 is a side view of the audio speaker component taken along lines 6—6 of FIG. 1; and,

FIG. 7 is a three-quarter perspective view of the audio speaker component.

1 Claim, 3 Drawing Sheets

FIG. 3.

FIG. 4.

FIG. 5.

FIG. 6.

FIG. 7.
